UNITED STATES PATENT OFFICE.

FREDERICK C. OVERBURY, OF MONTCLAIR, NEW JERSEY, ASSIGNOR TO FLINTKOTE MANUFACTURING COMPANY, OF RUTHERFORD, NEW JERSEY, A CORPORATION OF NEW JERSEY.

METHOD OF MAKING ROOFING ELEMENTS.

1,154,334.

Specification of Letters Patent. Patented Sept. 21, 1915.

Application filed January 21, 1915. Serial No. 3,481.

To all whom it may concern:

Be it known that I, FREDERICK C. OVERBURY, a citizen of the United States, and a resident of Montclair, in the county of Essex and State of New Jersey, have invented certain new and useful Improvements in Methods of Making Roofing Elements, of which the following is a specification.

This invention relates to a process of making waterproof coverings for roofs or side walls, such as may for simplicity be termed roofing elements, and it has for its object to provide a novel and economical method or process of making such elements.

According to my invention, I deposit upon the plastic coating of a waterproofed sheet of fibrous material bands or stripes of grit, such as crushed mineral material. Then, if desired, I deposit upon the intervening spaces grit of another color, shade or tint, thereby producing a novel and highly ornamental effect. If desired, the sheet may then be severed transversely into strips of the same length and breadth. When thus severed into strips, the elements so formed may be laid horizontally in vertically, overlapping rows, with the stripes or bands of one row either registering with or else breaking joint with those of the adjacent rows, to produce different effects. The stripes or bands of grit are produced by effecting a relative movement of the sheet and the hoppers or containers for the grit, as for example by feeding the sheet longitudinally beneath the ports leading from the hoppers, in which case the stripes or bands will be straight, but, by effecting at the same time a relative lateral movement of the sheet and the hopper, the stripes may be formed in curved or undulating lines to produce very pleasing effects. The roofing element may thus be in the form of a sheet, or else the sheet may be cut or severed into pieces of small size of the desired configuration.

On the accompanying drawings, I have illustrated conventionally roofing elements embodying the invention, and simple instrumentalities which may be employed in their manufacture.

Referring to said drawings, Figure 1 illustrates in plan view a machine which may be used for supplying grit to form on a sheet the stripes and intervening bands of

differently colored grit. Fig. 2 shows a side elevation of the same. Figs. 3 and 4 illustrate sections through the hoppers for feeding the grit. Fig. 5 represents a portion of the sheet having the stripes and bands of grit embedded therein. Fig. 6 represents a shingle strip cut therefrom. Fig. 7 represents a section through the element on the line 7—7 of Fig. 6. Fig. 8 shows how the shingle strips may be laid.

As a body or foundation, I employ any suitable fibrous material, such for example as felt, which is preferably saturated or impregnated with a waterproofing substance such as asphaltum, pitch or the like. This foundation is obtained in long sheets, preferably approximately 40 inches more or less in width, as indicated at 10. The sheet is drawn through rolls 11 or other devices for applying to one or both faces thereof a coating of waterproof adhesive material such as pitch or asphaltum in a soft and plastic state. After passing the rolls, the sheet is fed beneath hoppers 12, 13, or other forms of distributing or feeding devices for applying the grit to the soft coating thereon. The first hopper is shown as having separated delivery spouts or apertures 14, 14, through which grit of one color, say green, slate or black, may be dropped in separated streams upon the sheet traveling underneath, so that the grit will adhere to the coating in continuous and substantially parallel stripes 18. By reciprocating the hopper endwise, wavy or undulating stripes may be produced. In the hopper 13, the grit, which may for example be red, brown or of any other contrasting color, tint or shade, is dropped in a thin sheet upon the striped foundation sheet, and the grit which engages the uncoated portions of the adhesive coating will adhere thereto. The sheet may then be passed through one or more pairs of pressure and cooling rolls 16, 17 to embed the adhering grit into the adhesive coating, and, as the sheet passes over and through the rolls, those portions of the grit from the hopper 13, which fall upon the stripes of grit from the hopper 12, fall off or are dislodged, leaving the stripes showing with intervening bands or spans 19 of a different color. A fan or blower may be used for blowing the loose grit off from the

stripes, at a point between the hoppers and the first pair of rolls. From the final rolls the sheet may be wound up in a suitable roll and used in sheet form or else it may be 5 then advanced to a cutting machine not shown, to be cut transversely to form what I term shingle strips. In such case, the lines of division may be say 10 inches apart, so that each finished element will be approxi- 10 mately 40 inches in length and 10 inches in width or height, as shown in Fig. 6. The width of the several stripes and the intervening bands may vary, but I have 15 found that stripes approximately from $\frac{1}{4}$ to 1 inch wide produce a pleasing effect. The number of transverse or vertical stripes on the individual elements may be varied, and they may be formed equal distances apart, or at varying distances, to produce 20 any desired design. If desired, one end margin of the element may be striped and the other unstriped, as shown in the last-mentioned figure, so that, when the ends of the elements are abutted as shown in Fig. 8, 25 the stripes if parallel will be evenly spaced. If desired, however, the grit may be omitted from a narrow space at either or both ends of the element, to permit them to be overlapped lengthwise of the row, when laid. 30 If desired, the hopper 13 may be provided with partitions 20 to contain grit of different colors in the compartments formed thereby. These partitions may register with the 35 spouts or nozzles of the hopper 12, so that the bands or lines of grit between the stripes will differ in color therefrom and from each other to produce a variegated and ornamental effect.

In Fig. 7, which illustrates a lengthwise 40 section through a shingle strip, the impregnated and waterproofed foundation is indicated at 10, and the waterproof coating at 22, the stripes of grit at 18, and the intervening bands of grit at 19.

I have herein referred to the formation 45 of "stripes" and "bands" merely for the purposes of description. It is quite evident that the width of the stripes and bands may be varied as deemed advisable, so that the stripes may be as wide or wider than the bands of grit. In some cases, in lieu of supplying the second hopper, under which the sheet travels, with crushed mineral of 50 the nature of slate, granite or the like, I may supply the second hopper with pulverized mica or with talc so that the parallel spaces between the stripes will be left uncoated with grit but be prevented from sticking to adjacent layers or convolutions of the roofing material. In this case, the stripes will 55 in all probability be much wider than they are shown, this being permitted by employing discharge apertures from the first hopper of greater width than those illustrated. If desired, I may employ a trough located

in proximity to the first set of pressure or cooling rolls to receive the grit which falls from the fabric as indicated at 23 in Fig. 2.

Having thus explained the nature of my said invention, and described a way of making and using the same, although without attempting to set forth all of the forms in which it may be made or all of the modes of its use, what I claim is:

1. A method of making roofing elements 75 which consists in embedding longitudinal stripes of crushed mineral material in the adhesive coating of a sheet of roofing material, and then cutting said sheet transversely to form strips having said stripes crosswise 80 thereon.

2. A method of making roofing elements, which consists in applying an adhesive to the face of an elongated fibrous sheet, embedding lines of crushed mineral material 85 in said adhesive to form longitudinal stripes, and then cutting said sheet transversely to form sections of the same width and length.

3. A method of making roofing elements, which consists in applying an adhesive to 90 the face of an elongated fibrous sheet, embedding lines of crushed mineral material in said adhesive to form longitudinal stripes, and embedding crushed mineral material of another color in the uncoated portions of 95 said adhesive to form intervening bands.

4. A method of making roofing elements, which consists in applying an adhesive to the face of an elongated fibrous sheet, embedding lines of crushed mineral material 100 in said adhesive to form longitudinal stripes, embedding crushed mineral material of another color in the uncoated portions of said adhesive to form intervening bands, and cutting said sheet transversely into shingle 105 strips.

5. A method of making roofing elements, which consists in applying an adhesive to the face of an elongated fibrous sheet, embedding lines of crushed mineral material 110 in said adhesive to form longitudinal stripes, embedding crushed mineral material of another color in the uncoated portions of said adhesive to form intervening bands, and cutting said sheets into sections each having 115 said stripes and bands crosswise of its length.

6. The method of making roofing elements, which consists of moving an elongated sheet of fibrous material lengthwise, applying thereto a coating of waterproof adhesive 120 substance, passing said sheet under separated streams of crushed mineral material to cause said material to adhere in stripes to said adhesive substance, pressing said material into the said coating, and then cutting 125 said sheet transversely into sections.

7. The method of making roofing elements, which consists of moving an elongated sheet of fibrous material lengthwise, applying thereto a coating of waterproof adhesive 130

substance, passing said sheet under separated streams of crushed mineral material to cause said material to adhere in stripes to said adhesive substance, then passing said sheet through a shower of crushed mineral material of a different color to cause said material to adhere to said coating between said stripes, and removing the surplus crushed mineral material.

10 8. The method of making roofing elements, which consists of moving an elongated sheet of fibrous material lengthwise, applying thereto a coating of waterproof adhesive substance, passing said sheet under separated streams of crushed mineral material to cause said material to adhere in stripes to said adhesive substance, then passing said sheet through a shower of crushed mineral material of a different color to cause said material to adhere to said coating between said stripes, and then severing said sheet crosswise into sections of substantially the same length and width.

9. A method of making waterproof roofing, which consists of applying a waterproof adhesive to the face of a fibrous sheet, passing said sheet under separated streams of crushed mineral material to cause said material to adhere in lines to the face of said foundation, and embedding said material in the adhesive coating.

10. A method of making waterproof roofing, which consists of applying a waterproof adhesive to the face of a fibrous sheet, passing said sheet under separated streams of crushed mineral material, and simultaneously effecting a relatively lateral movement of the sheet and said streams, to cause said material to adhere to the adhesive in curved lines.

11. A method of making waterproof roofing, which consists of applying a waterproof adhesive to the face of a fibrous sheet, passing said sheet under separated streams of

crushed mineral material, simultaneously effecting a relatively lateral movement of the sheet and said streams, to cause said material to adhere to the adhesive in curved lines, embedding said material in said adhesive, and cutting said sheets into sections.

12. A method of making roofing elements, which consists in passing a sheet of fibrous material having an adhesive waterproof coating beneath separated streams of crushed mineral material to cause said material to adhere thereto in lines or stripes, and then passing said sheet under other streams of differently colored grit, to cause said last-mentioned material to adhere to the adhesive coating in other lines or stripes.

13. A method of making roofing elements, which consists in passing a sheet of fibrous material having an adhesive waterproof coating beneath separated streams of crushed mineral material to cause said material to adhere thereto in lines or stripes, then passing said sheet under other streams of differently colored grit, to cause said last-mentioned material to adhere to the adhesive coating in other lines or stripes, removing the surplus grit, and embedding the remaining grit in the said adhesive coating.

14. A process of making shingle strips which consists in coating an elongated sheet of fibrous waterproof material with a continuous layer of waterproof adhesive, completely covering the surface of said adhesive with a layer of crushed mineral, embedding said mineral in said adhesive, and severing said sheet transversely of its length into a plurality of shingle strips whose length is equal to the width of the sheet.

In testimony whereof I have affixed my signature, in presence of two witnesses.

“To that part of the claim in said specification which is in the following words:

“1. A method of making roofing elements which consists in embedding longitudinal stripes of crushed mineral material in the adhesive coating of a sheet of roofing material, and then cutting said sheet transversely to form strips having said stripes crosswise thereon.

“2. A method of making roofing elements, which consists in applying an adhesive to the face of an elongated fibrous sheet, embedding lines of crushed mineral material in said adhesive to form longitudinal stripes, and then cutting said sheet transversely to form sections of the same width and length.

“3. A method of making roofing elements, which consists in applying an adhesive to the face of an elongated fibrous sheet, embedding lines of crushed mineral material in said adhesive to form longitudinal stripes, and embedding crushed mineral material of another color in the uncoated portions of said adhesive to form intervening bands.

“4. A method of making roofing elements, which consists in applying an adhesive to the face of an elongated fibrous sheet, embedding lines of crushed mineral material in said adhesive to form longitudinal stripes, embedding crushed mineral material of another color in the uncoated portions of said adhesive to form intervening bands, and cutting said sheet transversely into shingle.

“5. A method of making roofing elements, which consists in applying an adhesive to the face of an elongated fibrous sheet, embedding lines of crushed mineral material in said adhesive to form longitudinal stripes, embedding crushed mineral material of another color in the uncoated portions of said adhesive to form intervening bands, and cutting said sheets into sections each having said stripes and bands crosswise of its length.

“6. The method of making roofing elements, which consists of moving an elongated sheet of fibrous material lengthwise, applying thereto a coating of waterproof adhesive substance, passing said sheet under separated streams of crushed mineral material to cause said material to adhere in stripes to said adhesive substance, pressing said material into the said coating, and then cutting said sheet transversely into sections.

“7. The method of making roofing elements, which consists of moving an elongated sheet of fibrous material lengthwise, applying thereto a coating of waterproof adhesive substance, passing said sheet under separated streams of crushed mineral material to cause said material to adhere in stripes to said adhesive substance, then passing said sheet through a shower of crushed mineral material of a different color to cause said material to adhere to said coating between said stripes, and removing the surplus crushed mineral material.

“8. The method of making roofing elements, which consists of moving an elongated sheet of fibrous material lengthwise, applying thereto a coating of waterproof adhesive substance, passing said sheet under separated streams of crushed mineral material to cause said material to adhere in stripes to said adhesive substance, then passing said sheet through a shower of crushed mineral material of a different color to cause said material to adhere to said coating between said stripes, and then severing said sheet crosswise into sections of substantially the same length and width.

“9. A method of making waterproof roofing, which consists of applying a waterproof adhesive to the face of a fibrous sheet, passing said sheet under separated streams of crushed mineral material to cause said material to adhere in lines to the face of said foundation, and embedding said material in the adhesive coating.

“12. A method of making roofing elements, which consists in passing a sheet of fibrous material having an adhesive waterproof coating beneath separated streams of crushed mineral material to cause said material to adhere thereto in lines or stripes, and then passing said sheet under other streams of differently colored grit, to cause said last-mentioned material to adhere to the adhesive coating in other lines or stripes.

“13. A method of making roofing elements, which consists in passing a sheet of fibrous material having an adhesive waterproof coating beneath separated streams of crushed mineral material to cause said material to adhere thereto in lines or stripes, then passing said sheet under other streams of differently colored grit, to cause said last-mentioned material to adhere to the adhesive coating in other lines or stripes, removing the surplus grit, and embedding the remaining grit in the said adhesive coating.”

[Official Gazette December 2, 1919.]
